UNITED STATES PATENT OFFICE

FRANK L. VAN DUSEN, OF NORTH TONAWANDA, NEW YORK, ASSIGNOR TO THE RUST-LESS RULE CO., INC., OF BUFFALO, NEW YORK, A CORPORATION OF NEW YORK

BLADE HOLDER

Application filed March 27, 1928. Serial No. 265,172.

This invention relates to the type of scraping and cutting tools comprising generally a handle carrying members between which a blade is removably clamped.

5 Its chief object is the provision of a simple tool or holder of this character which permits the ready application and removal of the blade and which can be cheaply manufactured.

10 Another object is to so construct the tool that one of its blade-clamping members may perform the additional function of a guard when the device is not in use.

In the accompanying drawings:—

15 Figure 1 is a perspective view of the blade-holder, showing the same adjusted to expose the edge of the blade. Figure 2 is a similar view with the parts in position to apply or remove a blade. Figure 3 is a perspective 20 view of the clamping plate. Figure 4 is a similar view of a type of blade which may be clamped in the holder. Figures 5 and 6 are transverse sections of the head of the holder, showing different adjustments of the 25 clamping plate.

Similar characters of reference indicate corresponding parts throughout the several views.

The tool comprises a handle 10 terminating 30 at its front end in a flat cross head 11, and a clamping plate 12 imposed on the cross head and having the same general dimensions as the head. Between these members a suitable scraping or cutting blade 13 is held. Old 35 or new razor blades may be used for this purpose, the blade shown in the drawings being of the well-known double-edge type with three holes.

The head 11 has a central opening 14 adapted 40 to register with the corresponding hole of the blade and a pair of lugs or stops 15 located on the face of the head on opposite sides of said opening and adapted to pass through the end holes of the blade to hold 45 it against backward and endwise movement on the handle-head. These lugs are preferably struck up from the head and arranged to face forwardly, as shown, with their free end portions disposed substantially horizontal 50 tal or parallel to the cross head in spaced

relation thereto. The blade 13 is adapted to rest on the cross head with the horizontal portions of the lugs 15 overlying the blade adjacent its end holes and the vertical portions of said lugs forming stops for alining 55 the blade centrally on the cross head and insuring the register of the central blade opening with the cross head opening 14.

The clamping plate 12 is provided on its underside with a central stud 16 adapted to 60 interlock with the center hole of the blade and the corresponding hole 14 in the head 11, and on opposite sides of the stud said plate has transverse slots or apertures 18 adapted to receive the lugs 15, to hold the 65 plate from lateral and backward displacement on the handle-head. These slots extend beyond the front and rear edges of the central stud 16 and are of a length substantially twice that of the lugs 15. 70

A lever 19 fulcrumed on the handle 10 and engaging the plate 12 serves to clamp the blade securely between these parts and to keep their retaining members interlocked. 75 In the preferred construction shown, this lever is pivoted between its ends to the handle by a pin 20 located adjacent to and centrally of the plate 12, the short upper arm of the lever being offset and normally overlapping said plate, while its long lower arm 80 overlies and bears against the face of the handle. To apply a blade to the holder, the clamping lever is swung crosswise of the handle, as shown in Figure 2, and the clamping plate 12 is removed from the head 11. A 85 blade is then engaged with the lugs 15, the clamping plate is replaced to interlock its stud 16 with the blade and the slots 18 with said lugs and the lever is turned parallel with the handle, thus locking the clamping plate 90 and the blade to the head.

To substitute another blade for a dull or broken one, these operations are obviously reversed.

The clamping plate 12 is preferably reversible on the handle-head and its slots are arranged eccentrically to the plate or nearer one of its longitudinal edges than the other, as shown in Figure 3. By this arrangement, 95 upon bringing the edge of the plate nearest 100

the slots opposite the front edge of the handle-head, the cutting edge of the blade is uncovered for service, as shown in Figures 1 and 5, with the free edges of the lugs 15 abutting against one end of the slots 18 in the clamping plate 12, while upon reversing the plate from this position, its other edge extends beyond the cutting edge of the blade and covers it as shown in Figure 6 with the free edges of said lugs 15 abutting against the opposite ends of said slots, thereby protecting the hands when the tool is not in use. In either position of the clamping plate its stud 16 engages the opening 14 in the cross head 11 and one end or the other of the slots 18 abut against the lugs 15, thus positively holding the clamping plate against accidental displacement.

This improved tool or holder is especially serviceable as a scraper, for example, for removing paper from walls or paint from various surfaces, but it is also useful as a cutter.

Being composed of few parts, it can be produced at small cost.

I claim as my invention:—

1. A blade-holder of the character described, comprising a handle having a cross head, said head being provided centrally with an opening and on opposite sides of said opening with blade-engaging lugs adapted to engage corresponding openings in the blade and having their free end portions disposed in spaced parallel relation to the cross head, a blade-clamping plate imposed on said head and having a stud arranged to engage an opening of the blade and the opening of said head, and apertures to receive said lugs, the latter constituting stops for alining the blade on the cross head to bring its opening into register with the cross head opening, and a clamping lever fulcrumed between its ends on said handle and overlapping said clamping-plate.

2. A blade holder of the character described, comprising a pair of superposed blade-clamping members and means for clamping them together, one of said members having a stop-lug and the other being reversible and having a transverse slot engaging said lug and of a length substantially twice that of the engaging portion of the lug, said slot being arranged nearer one longitudinal edge of said slotted member than the other, to uncover the cutting edge of the clamped blade in one position of the reversible member and cover said edge in the other position of the member, one end of the slot engaging the lug in one position of the parts and the other end of said slot engaging its lug in the other position of the parts.

3. A blade holder of the character described, comprising a handle having a cross head, said head being provided centrally with an opening and on opposite sides of said

opening with blade-engaging lugs, said lugs facing forwardly with their free end portions in spaced parallel relation to the cross head, a blade-clamping plate imposed on said head and having a stud arranged to engage an opening of the blade and the opening of said head and also having transverse slots to receive said lugs, said clamping-plate being reversible on said cross head and its slots being located nearer one longitudinal edge thereof than the other and being substantially twice as long as the blade engaging lugs, and means for holding said clamping-plate in position on the cross head.

4. A tool of the character described, comprising a pair of superposed blade-clamping members, one of said members consisting of a handle having a cross head at one end and the other consisting of a clamping plate of substantially the same dimensions as the cross head, a cutting blade adapted to be clamped between said members and having a plurality of alining openings therein, said cross head having an opening therein and forwardly-facing blade-engaging lugs struck from its top side and having their free end portions disposed in spaced parallel relation to the cross head, such space being sufficient to receive the contiguous portions of the blade beneath said lugs, the clamping plate having a stud projecting from its bottom side for engagement with one of the blade-openings and said cross head opening and also having transversely-elongated openings for receiving the cross head lugs and against one end of which said lugs are adapted to abut, and means mounted on the handled member for clamping the other member thereto.
